Primary Examiner — Susan Bennett Hattan

Assistant Examiner — Suzanne E Tisdell

(57) **CLAIM**

The ornamental design for a vehicle deck lid, as shown and described.

DESCRIPTION

FIG. 1 is a front and right side perspective view of a vehicle deck lid.

FIG. 2 is a front elevation view thereof;

FIG. 3 is a left end elevation view thereof; and,

FIG. 4 is a top plan view thereof.

The right end elevation view is omitted, because the right end elevation view is a mirror image to the left end elevation view.

The broken lines shown in the drawings depict portions of the vehicle deck lid that form no part of the claimed design. The shade lines in the figures show contour and not surface ornamentation.
